a special partnership

Application August 30, 1940, Serial No. 354,816

4 Claims. (Cl. 255—1.6)

This invention relates to side tracking apparatus.

An object of the invention is to provide apparatus of the character described specially designed for forming a side window in a well casing through which further drilling operations may be continued.

In drilling wells it often happens that the well becomes obstructed so that drilling operations cannot be continued through the original well bore; or the original bore may become deflected to such an extent that it becomes necessary to straighten the same. In either of such events a whipstock may be lowered into the well and oriented and anchored in place at the desired location and a milling tool then lowered into the well to co-act with the whipstock and whereby a vertically elongated window may be formed through the side of the casing through which further drilling may proceed.

It is another object of the present invention to provide apparatus embodying a novel type of whipstock for carrying on the side tracking operation hereinabove referred to.

The invention embodies a novel type of whipstock wherein the guide for the milling tool comprises antifriction roller bearings which will hold the milling tool against the work, this form of the apparatus being specially designed for forming a window in the casing either by milling the casing, if this can be done, or by shattering the side wall of casing which has become too hard to be milled out.

With the above and other objects in view the invention has particular relation to certain novel features of construction, operation and arrangement of parts examples of which are given in this specification and illustrated in the accompanying drawing wherein—

Figure 1 shows a fragmentary, vertical, sectional view of the whipstock showing the milling tool in cooperation therewith.

Figure 2 shows a vertical sectional view showing the whipstock in elevation.

Figure 3 shows a cross sectional view taken on the line 3—3 of Figure 1, and

Figure 4 shows an enlarged, fragmentary, elevational view of the type of whipstock shown in Figures 1 and 2.

Referring now more particularly to the drawing wherein like numerals of reference designate the same parts in each of the figures, the numeral 1 designates a whipstock whose lower end is approximately cylindrical and which may be set in the well casing 2 at any desired elevation. When

lowered to the point where it is to be set it may be fixed in the casing against further downward movement in any conventional manner; as shown, it is provided with an upwardly and outwardly tapering face 3 and an upwardly tapering wedge shaped slip 4 works against the face 3. In the present illustration a rod 5 is attached to the slip 4 and extends on down into the well and is of a length to cause the slip to set at the desired elevation. When the whipstock is lowered until the lower end of the rod 5 lands on bottom, it will then force the slip 4 upwardly relative to the whipstock and outwardly into engagement with the well casing. The slip has the external downwardly pitched teeth which will engage the casing and set the whipstock against downward movement during subsequent milling operations. The whipstock may be attached to the lower end of the milling tool as 6a which in turn is carried 10 at the lower end of the drill stem 7. It may be so attached by means of a suitable shear pin as 8 and when it is let down into the well and set the pin may be sheared to allow the milling tool to move on downwardly as hereinabove explained.

15 The whipstock is provided with the upper and lower downwardly and outwardly tapering faces 9 and 10 which are spaced apart to provide the vertical face 11 between them. These faces are arcuate in horizontal cross sectional contour.

20 It sometimes happens that the casing 2 is so hard that it cannot be readily cut away by a mill in forming the window. Usually, however, the very hard casing can be broken so as to form a window therethrough. For this purpose a special 25 type of whipstock and mill has been provided as shown in Figures 1 to 4, inclusive. Series of rollers 17 are mounted on the vertical face 11 of the whipstock. These rollers are mounted to rotate on vertical axes. The mill 6a, to be used in such 30 case, has its lower face formed into an approximately inverted conical shaped guide 6b which engages against the inside of the casing, as shown in Figure 1. As the work progresses, this mill 35 operates against the casing as well as against the rollers 17 and as it moves downwardly it is wedged between said rollers and the casing and the weight of the drill stem above will cause it to 40 crush the side of the casing against which it operates thus gradually forming an elongated window through the side of the casing.

45 The milling tool is provided with external cutting teeth, as shown, and the form of mill shown in Figure 1 will either shatter or cut away the 50 casing so as to effectively form an elongated win-

55

dow therethrough through which subsequent drilling operations may be carried on.

When the lower tapering face 10 has been reached by the milling tool 6a, said tool is withdrawn and a special type of mill is then employed to complete the work of cutting the window.

The drawing and description are illustrative merely of the principle of the invention and are not intended to be restrictive except as defined by the appended claims.

What we claim is:

1. In side tracking apparatus for wells, a whip-stock shaped to enter a well casing and having a longitudinal surface arranged to be spaced from one side of the casing when the whipstock is in the casing, anti-friction means arranged along said surface to contact with a milling tool as said tool is lowered between said surface and the opposing side of the casing and whereby the milling tool will be forced through said side of the casing as the tool is lowered and rotated.

2. In side tracking apparatus for wells, a whip-stock shaped to enter a well casing, means for anchoring the whipstock to the casing, said whip-stock having a longitudinal surface above the anchoring means and spaced from one side of the casing when the whipstock is in the casing, anti-friction means arranged on said surface in position to contact with a milling tool as said tool

is lowered between said surface and the opposing side of the casing and whereby the milling tool will be forced through said side of the casing as the tool is lowered and rotated.

3. In side tracking apparatus for wells, a whip stock shaped to enter a well casing and adapted to force a milling tool through the side of said casing, said whip-stock having a lower downwardly and outwardly tapering face and an approximately vertical face above the tapering face and anti-friction rollers disposed along the vertical face of the whip stock approximately from end to end thereof.

4. Side tracking apparatus for wells comprising a well casing, a milling tool, a stem for driving the tool, a whip stock shaped to enter the well casing and adapted to force the milling tool through the side of said casing, said whip stock having upper and lower downwardly and outwardly tapering faces and an approximately vertical face between said tapering faces and rotatable, bearing means extending from the upper to the lower end of the vertical face of the whip stock and arranged to hold the milling tool in contact with the casing and out of contact with said vertical face.

GEORGE J. BARRETT.
